UNITED STATES PATENT OFFICE.

JOHN ZILLIOX, OF ORCHARD PARK, NEW YORK.

WRENCH.

Application filed February 7, 1921. Serial No. 442,906.

To all whom it may concern:

Be it known that I, JOHN ZILLIOX, a citizen of the United States, residing at Orchard Park, in the county of Erie and State 5 of New York, have invented new and useful Improvements in Wrenches, of which the following is a specification.

This invention relates to a wrench and has for its principal object the production of a 10 strong, durable and efficient wrench which can be produced at low cost from stock bar metal without the use of dies for forming the jaws and shank of the wrench but instead can be cut in gangs by the use of an 15 ordinary milling machine and assembled by a simple bending operation.

In the accompanying drawings: Figure 1 is a side elevation of my improved wrench. Figure 2 is a longitudinal section of the 20 same. Figures 3, 4 and 5 are cross sections on the correspondingly numbered lines in Fig. 2. Figures 6 and 7 are perspective views of the fixed and movable jaws and associated parts showing the condition of the same before assembling. Fig. 8 is a horizontal section on line 8—8, Fig. 2.

Similar characters of reference indicate corresponding parts throughout the several views.

30 10 represents the longitudinal bar or shank of the wrench which is preferably constructed of a bar of metal which is rectangular in cross section and can be cut in suitable lengths from a stock bar without 35 any waste excepting finishing the rear end of the same by rounding the corners, or otherwise.

11 represents the front or fixed jaw of the wrench which has its inner longitudinal 40 edge 12 engaging with the inner longitudinal edge of the shank and provided with two cheeks 13, 13, which extend transversely from this jaw along opposite sides of the shank and are provided at their outer 45 longitudinal edges with lips 14 which are bent toward each other against the outer longitudinal edge of the shank. The integral blank for this jaw and its cheeks and lips is first cut from a stock metal bar which

50 can be done with practically no waste of metal after which a longitudinal groove is cut in the back of the blank by milling to form the wings which subsequently constitute the cheeks and lips, as shown in Fig.

55 6. This operation especially when cutting a gang of blanks at one time, can be done at

a very low cost. Thereafter the wings of a front jaw are placed astride of the front end of the shank and then the extremities of the wings are bent toward each other and 60 against the outer longitudinal edge of the shank with a cold sheet, whereby the front jaw and shank are securely connected and capable of being used without further 65 attention. It is preferable however to additionally secure the shank and front jaw together by fastening a pin 15 transversely in corresponding openings in the cheeks of the front jaw and the adjacent intervening part of the shank, as shown in Figs. 1, 2 70 and 3.

16 represents the movable rear jaw of the wrench which co-operates with the front jaw for grasping articles. This jaw is formed integrally with a carriage which slides 75 lengthwise on the shank and is provided with a cross piece 17 upon the front end of which the movable rear jaw is arranged. This cross piece is arranged lengthwise of the inner longitudinal edge of the shank and 80 is provided with two cheeks 18, 18 which project laterally from the cross piece along opposite sides of the shank and has its extremities bent toward each other in the form of lips 19 along the outer longitudinal edge 85 of the shank. The cross piece, cheeks and lips of the carriage do not fit tightly against the shank in order to permit the same to slide freely lengthwise thereon. The blank for 90 the rear movable jaw and its carriage is also cut from a stock metal bar, after which a groove is milled into the back of the same to form the two wings from which the two cheeks and lips of the respective carriage 95 are subsequently constructed. When milling a gang of such carriages the cost of the same is reduced to a minimum.

By constructing the shank and front and rear jaws and the means of mounting the same on the shank in the manner described, 100 the parts can be made of high grade material at very low cost and equal, if not exceed in efficiency, wrenches in the manufacture of which expensive dies have usually been employed for forging the metal into 105 the desired shape. These dies are particularly expensive when making the larger sizes of wrenches having comparatively long shanks or handles whereas the length of the shank or the size of the jaws in the present 110 invention is of no particular consequence. Any suitable means may be employed for

adjusting the movable jaw toward and from the fixed jaw, those shown in the drawings being suitable and preferred and comprising a gear rack 20 formed on the inner longitudinal edge of the shank, a worm 21 engaging its thread with said rack and arranged in a recess 22 formed in the carriage in rear of the movable jaw, and a pivot pin 23 upon which said worm is journaled which is supported with its unthreaded front end in an unthreaded opening 24 in the front part of the cross piece of the carriage while its externally threaded rear end 25 engages with an internally threaded opening 26 in the rear part of the cross piece of the carriage, as shown in Figs. 1, 2 and 5. Upon turning the worm by engaging the fingers with opposite sides of the knurled thread thereof, the same will cause the movable jaw to either advance or recede and thus permit of adapting the jaws to the object to be grasped.

If desired, the connection between the fixed jaw 11 and the shank 10 may be effected by bending the opposing edges of the lips 14 downwardly in the form of hooks 27 into a recess 28 formed in the front part of the upper edge of the shank, as shown in Figs. 2, 3 and 8. Turning or twisting of this jaw on the shank may also be resisted when subjected to heavy strains by means of transverse ribs or projections 29 arranged on the inner sides of the cheeks 13 and engaging with recesses or transverse grooves 30 arranged on the opposite sides of the front part of the shank, these ribs being formed and engaged with these grooves by pressing the cheeks 13 against opposite sides of the shank. The hooks 27 and recess 28 and the ribs 29 and grooves 30 may be employed either in addition to the fastening pin 15 or the same may be employed to the

exclusion of the same, according to the amount of strength desired in the wrench and the purpose for which the same is to be used.

I claim as my invention:

1. A wrench comprising a bar, and a jaw arranged along the inner edge of the bar and provided with two outwardly projecting cheeks which are arranged on opposite sides of said bar and have lips at their outer ends which project toward each other and overhang the outer edge of the bar, the outer edge of the bar being provided with a recess, and said lips being constructed in the form of hooks which engage said recess.

2. A wrench comprising a bar, and a jaw arranged along the inner edge of the bar and provided with two outwardly projecting cheeks which are arranged on opposite sides of said bar and have lips at their outer ends which project toward each other and overhang the outer edge of the bar and the opposing sides of said bar, said bar and cheeks being provided with interlocking shoulders which prevent longitudinal movement of these parts on each other.

3. A wrench comprising a bar, and a jaw arranged along the inner edge of the bar and provided with two outwardly projecting cheeks which are arranged on opposite sides of said bar and have lips at their outer ends which project toward each other and overhang the outer edge of the bar, the outer edge of the bar being provided with a recess, and said lips being constructed in the form of hooks which engage said recess and the opposing sides of said bar and cheeks being provided with interlocking shoulders which prevent longitudinal movement of these parts on each other.

JOHN ZILLIOX.
